CONDENSER FOR COTTON AND OTHER FIBERS

William Shaw and Eliot B. MacLean, Saco, Maine,
assignors to Saco-Lowell Shops, Boston, Mass.,
a corporation of Maine

Application February 14, 1939, Serial No. 256,294

13 Claims. (Cl. 19—156)

This invention relates to machines or apparatus for separating cotton or other fibrous material from a stream of air in which it is being conveyed. An apparatus of this type is commonly referred to as a "condenser."

It is a very common practice to convey cotton from a storehouse to a mill, or from one operation or department in a mill to another, by means of a current of air guided through a conduit or pipe. At the point where the cotton is to be delivered it is screened out of the conveying current by a condenser. Thus in a textile mill or other plant in which fiber in loose form is handled, many of these condensers may be used. Frequently they are built into, or form part of, a machine, but in many instances, also, they are installed as separate and independent units.

A typical condenser comprises a rotary screening drum mounted in a casing into which the fiber laden current of air is conducted, the arrangement being such that the current is directed through the peripheral screening surface of the drum and is discharged axially through one or both of its ends. During such travel the fiber is deposited on the screening surface and is carried by the rotary motion of the drum into the range of operation of a pair of delivery rolls which strip the fiber from the drum and discharge it from the apparatus. In order to enable these rolls to perform their functions it is necessary to adjust them from time to time. For the same reason it is customary to locate curved shields or vanes inside the drum closely adjacent to its peripheral surface and of considerable circumferential extent so that they will substantially prevent the flow of air through the section of the drum from which delivery rolls remove the fiber. These vanes or shields also get out of correct position at times and must be readjusted. Accordingly, both of these accessory elements require care and attention on the part of someone, and are the cause of much trouble and annoyance.

It has been the custom heretofore to build condensers generally with reference to the requirement of the particular installation and, consequently, more or less to order. This fact has necessarily added to the expense of manufacture and is often the cause of delay in making shipments and filling orders.

The present invention aims to improve condensers with a view to eliminating much of the trouble and annoyance heretofore experienced with them, reducing the manufacturing expense, and devising a construction readily adaptable to a wide variety of conditions and which may be regarded as standard for many requirements of textile mills. It is also an object of the invention to provide an apparatus of this kind which will demand materially less care and attention than prior art constructions and will be less likely

to get out of order or to require cleaning and adjustment.

A further object of the invention is to devise a complete condenser unit including a screening cylinder, a blower cooperating therewith, means for stripping the screened fiber from the cylinder and discharging it, together with the driving connections between the various elements, the entire unit being portable and capable of being installed quickly and conveniently at any desired point where it is to be used.

The nature of the invention will be readily understood from the following description when read in connection with the accompanying drawings, and the novel features will be particularly pointed out in the appended claims.

In the drawings,

Figure 1 is a plan view of a condenser unit constructed in accordance with this invention;

Fig. 2 is a longitudinal, sectional view approximately on the line 2—2, Fig. 1;

Fig. 3 is a transverse, sectional view approximately on the line 3—3, Fig. 2;

Figs. 4 and 5 are side views, largely diagrammatic in character, indicating different arrangements in which the parts of the unit may be associated with each other;

Figs. 6 and 7 are fragmentary, longitudinal, sectional views showing different positions of the intake chute; and

Fig. 8 is a vertical, sectional view approximately on the line 8—8, Fig. 1.

Referring first to Figs. 1, 2 and 3, the condenser unit there shown comprises a rotary drum, open at both ends, and including a suitable number of spiders 2, the circumferential edges of which support a cylindrical screen 3. The unit also includes a blower, indicated in general at 4. These members are mounted in a casing provided with suitable chambers to receive the drum and blower, respectively. The casing is made at its opposite sides with conduit or pipe sections 5—5 providing ducts or flues 6—6, Fig. 3, which afford communication between the discharge or outlet ends of the drum 3 and the intake ends 45 of the blower 4. Thus the blower will draw air from the screening chamber through the circumferential surface 3 of the drum out through the ends of the latter and will discharge it through the outlet 7, Fig. 2, of the blower.

The fiber laden stream of air to be screened is led into the casing through an intake chute or funnel 8 and flows through the screening drum in the manner just described. During such flow the fiber is strained out of the air stream by the screening surface 3 and as the drum revolves in the direction of the arrow in Fig. 2 the material so deposited on the surface of the screen is carried into the range of operation of a stripper roll 10. This roll may conveniently consist of

a metal drum having a series of radial metal bars 11 welded thereto and extending across the drum from one end thereof to the other, and a series of stripper blades 12 made of leather, or equivalent material, secured to the bars 11 by similar bars or strips 13 bolted to the parts 11. The stripper revolves in a short discharge chute 14, preferably in the same direction as the drum 3 but at a considerably higher peripheral speed, so that the flexible blades 12 sweep the fiber from the screening surface 3 and hurl this stock through the discharge chute. In addition to performing this function the stripper also seals said chute against any material flow of dust laden air through it.

From the foregoing it will be seen that the entire circumferential area of the screening drum 3 is open to the simultaneous flow of the air stream therethrough; that baffles or vanes inside the drum have been completely eliminated so that the difficulties heretofore occasioned by their use are avoided; and that the usual stripper rolls have been replaced by a single roll of simple and rugged construction which will perform effectively until the flexible blades 12 are worn out. Thus these factors which have heretofore been the cause of much trouble and annoyance are either eliminated or so changed that the difficulties with them are completely avoided or greatly minimized.

In that part of the screening chamber through which successive portions of the screen 3 travel immediately after leaving the stripper, there is a tendency for the air circulation to be relatively sluggish simply due to the position of the drum in the chamber and the relationship of this portion of the chamber to the direction in which the incoming air stream enters the chamber. If, in addition, it is necessary to use a deflector plate, such as that shown at 15, Fig. 2, which is not required in the arrangement there illustrated but is advisable with other positions of the intake chute, then the air flow in the lower left-hand corner of the chamber may become so sluggish that dust or fiber will collect there to an undesirable degree. In order to prevent this action, the bottom plate 17 of the casing is slotted, as shown at 16 in Figs. 1 and 2, and a damper plate 18 is mounted immediately below this slotted area and is guided on bolts 20-20 so that it can be adjusted to open the slots 16 more or less or to close them completely. Thus a restricted and controlled admission of air into this part of the chamber is provided where it prevents any substantial accumulation of dust or fiber in this region.

In order to reduce the expense of manufacture of the apparatus and to provide for convenient interchange or rearrangement of the parts, the casing preferably is made of metal plates bolted or otherwise secured together. Preferably, also, it is made in two sections, namely, a screening section A and a blower section B. The screen section A includes side plates 21-21 provided with flanged margins. Connecting these plates are additional top and bottom plates or panels 22 and 27, respectively, and front and rear panels 23 and 24. All of these panels likewise are provided with flanged edges and they are secured to the side plates by bolts. The curved plates of the chute 14 similarly are secured to adjacent casing parts. Additional inclined plates 33 and 34, Fig. 2, connect the upper and lower edges, respectively, of the front panel 23 to the adjacent plates. The rectangular inner end of the intake chute 8 also

is secured to the rear plate 24 by bolts and to the top plate 22 by a small panel 35 bolted both to the parts 8 and 22.

The blower section B comprises side plates 25-25 similar to the plates 21-21 but does not have top, bottom, front, or rear plates. The side plates are secured together by a spacing rod 26 and by the blower casing. This casing includes a main section 27 or rotor casing in which the fan 28 is housed and two tubular intake sections 30-30 opening into the ducts 6-6 and each welded to metal plates at opposite ends thereof which are bolted to the end plates 25 and the casing 27, respectively. These plates at the outer ends of the sections 30 are shown at 31 in Fig. 1 and are indicated in dotted lines in Fig. 2.

The two sections A and B are secured together by rows of bolts 32-32, Fig. 1, passing through the abutting vertical flanges of the side plates of the two sections.

The conduit or flue sections 5-5 preferably are made integral with the side plates 21-21 and their left-hand ends, Fig. 1, are telescoped within similar sections 5'-5' integral with the side plates 25-25 of the blower section. As shown in Fig. 1, the opposite ends of the ducts 5-5 are closed by caps 36-36.

This construction provides an arrangement which can be easily modified to suit a great variety of conditions. For example, if it is desired to shift the intake chute 8 into the position shown in Fig. 5, this can readily be done by disconnecting the chute and the plate 35, Fig. 2, turning them into the desired position and then bolting the plate 35 to the upper edge of the plate 24 and the free edge of the chute to the left-hand edge of the panel 22. Similarly, it can be shifted to the right-hand side of the screen section, as shown in Figs. 6 and 7, the parts in those figures being designated by the same numerals used for corresponding parts in the other figures. When the chute 8 is in the position shown in either Figs. 5 or 6, the deflector plate 15 is useful in producing a better distribution of the air flow throughout the chamber and preventing the cotton from being carried by its own momentum into the portion of the screening chamber behind the drum 3 where, as above stated, the circulation naturally is somewhat sluggish. Also, when the chute is in the position shown in Fig. 7, the plate 15 can be shifted to the right-hand side of the screening chamber where it will co-operate with adjacent parts in essentially the same manner that it does when the chute is in the position illustrated in Fig. 5. Preferably this plate is equipped with a tip or edge member 15' which is adjustable toward and from the drum 3 so that the relationship of this deflector or baffle member to the drum can be varied to suit different operating conditions.

The two sections A and B of the casing also can be reversed, if desired, while still preserving the operative relationship of the blower and screen section to each other. Fig. 4 shows the blower section secured to the right-hand side of the screen section instead of at the left-hand side thereof as in Figs. 2 and 5. In order to make this change in relationship of the parts it is merely necessary to unbolt the section B from the section A, to remove the caps 36, Fig. 2, and then to abut the flanges of section B against the corresponding parts of the other section and bolt the two together. In bringing the parts together in their new relationship, the ducts 5' at opposite sides of the blower section are slipped over or telescoped

upon the corresponding ducts 5 of the screen section, and a cap 36 is placed on the left-hand end of each duct 5. Thus the cooperative relationship of the parts is maintained undisturbed 5 in their new positions.

The drum 3, blower fan 28 and stripper 10, include driving shafts individual to them indicated, respectively, at 38, 39 and 40. The drum shaft 38 is supported in ball bearings or roller bearings 10 41—41 secured in the walls of the flues 5—5, and this shaft carries a pulley 42. The other two shafts 39 and 40 are similarly supported in ball or roller bearings, and they carry pulleys 43 and 44 and are operatively connected together by a belt 45, Fig. 1. The stripper roll shaft 40 also has another pulley 46 secured to it, and it is belted to the drum pulley 42, as shown at 47. Thus all the shafts of the condenser unit are connected directly to each other, and their operative relationship 20 is such that it is not disturbed by the reversal of the sections A and B, as shown in Fig. 4. The blower shaft has a pulley 48 for convenience in connecting the unit to any suitable source of power. By mounting the shafts in ball or roller 25 bearings, they may be packed with a sufficient supply of lubricant to run without attention for many months.

Provision is also made for adjusting the rotor casing 27 of the blower into various positions 30 where it will discharge its air in different directions. This is a great convenience in adapting the condenser to use in different relationships. It will be observed that the casing 27 is secured to the end plates 25—25 by the flanges 31—31 35 and their bolts 50, Figs. 1 and 8. Consequently, by removing these bolts the casing 27 with its intake ducts 38—38 may be adjusted around the blower shaft 39 into any one of four different positions. When so adjusted it may be secured 40 rigidly in its new position. In addition, the blower casing may be reversed end for end in the blower section B, although this is not quite so easily accomplished. Two of these different positions of the blower are shown in Figs. 4 and 5.

From the foregoing it will be appreciated that 45 the invention provides a condenser unit of extraordinary adaptability to different locations and the requirements of different installations. This characteristic is valuable both to the ultimate 50 user and also to the manufacturer. It permits the former to use the same unit in a great variety of locations and with different machines, and it affords the manufacturer a degree of standardization of parts and assembly which materially 55 reduces the cost of production. So far as possible, those parts and elements requiring frequent inspection and adjustment have been eliminated, and the apparatus is capable of continuous operation over long periods without attention of any 60 kind. The fact that the condenser unit is a complete and compact structure including not only the elements necessary for its operation, but also the driving connections between those elements, and that it is of a readily portable nature, saves 65 trouble and expense in installation, it merely being necessary to mount it in the position where it is to be used and to connect it to any convenient source of power. If desired for any reason, either section may be disconnected from the 70 other and used alone.

While we have herein shown and described a typical embodiment of our invention, it will be evident that modifications may be made within 75 the spirit and scope of the invention.

Having thus described our invention, what we desire to claim as new is:

1. A condenser unit for screening fiber out of an air stream, comprising an open-ended rotary screening drum, a blower, a casing having chambers in which said drum and blower are mounted, respectively, said casing having ducts for conducting air from said drum into the intake of said blower, a roll mounted in said casing in cooperative relationship to said drum for stripping therefrom the fibrous material strained out of the air stream by the screening surface of said drum, an intake chute for conducting the incoming fiber laden air stream into said drum chamber, said drum being substantially unobstructed internally so that air can flow from said drum chamber through approximately the entire circumference of the drum, an outlet chute through which said stripper roll discharges the material removed from said drum, and means for admitting a restricted flow of air into a part of said drum chamber outside said drum and remote from said inlet and outlet. 5 10 15 20

2. A condenser unit for screening fibers out of an air stream, comprising an open-ended rotary 25 screening drum, a blower, a casing having chambers in which said drum and blower are mounted, respectively, said casing having ducts for conducting air from said drum into the intake of said blower, a roll mounted in said casing in cooperative relationship to said drum for stripping therefrom the fibrous material strained out of the air stream by the screening surface of said drum, said drum being so positioned in said casing as to reduce the circulation of fiber laden 30 35 air in contact with a portion of the screen adjacent to the stripper roll, and means for admitting a restricted flow of air into said part of the drum chamber outside said drum and in which the circulation of air otherwise would be 40 sluggish.

3. A condenser unit for screening fibers out of an air stream, comprising a rotary screening drum, a casing in which said drum is mounted, means for stripping from the peripheral surface 45 of said drum the fibrous material filtered by it out of the air stream, an intake chute for conducting the incoming fiber laden air stream into the screening chamber in said casing, said casing having an opening admitting a restricted 50 flow of air from outside said casing into a part of said chamber outside said drum and in which the circulation of said fiber laden air stream is relatively sluggish.

4. A condenser unit for screening fibers out of an air stream, comprising a rotary screening drum, a casing in which said drum is mounted, means for stripping from the peripheral surface 55 of said drum the fibrous material filtered by it out of the air stream, and an intake chute for conducting the incoming fiber laden air stream into the screening chamber in said casing, said casing and said chute including removable parts adapted to be rearranged to connect said chute to different parts of said casing, in all of which 60 it serves to direct said air stream into said chamber. 65

5. A condenser unit for screening fibers out of an air stream, comprising a rotary screening drum, a casing in which said drum is mounted, 70 means for stripping from the peripheral surface of said drum the fibrous material filtered by it out of the air stream, and an intake chute for conducting the incoming fiber laden air stream into the screening chamber in said casing, said 75

casing including removable panels affording access to the screening chamber at different points around said drum, and said chute being adapted to be connected to any one of a plurality of the 5 openings normally closed by said panels.

6. A condenser unit for screening fibers out of an air stream, comprising a rotary screening drum, a casing in which said drum is mounted, means for stripping from the peripheral surface 10 of said drum the fibrous material filtered by it out of the air stream, and an intake chute for conducting the incoming fiber laden air stream into the screening chamber in said casing, said casing having parts interchangeable to secure 15 said chute thereto in different operative relationships.

7. A condenser unit for screening fibers out of an air stream, comprising an open-ended rotary screening drum, a blower, a casing having chambers 20 in which said drum and blower are mounted, respectively, with their axes parallel to each other, said casing having ducts for conducting air from said drum into the intake of said blower, means for stripping from said drum the fibrous material, strained out of the air stream by the screening surface of the drum and discharging such material from said casing, said casing comprising two sections containing said respective chambers, and means for securing said sections together in different positions while preserving the operative relationship of said blower, 25 drum and ducts to each other.

8. A condenser unit for screening fibers out of an air stream, comprising an open-ended rotary 30 screening drum, a blower, a casing having chambers in which said drum and blower are mounted, respectively, with their axes parallel to each other, said casing having ducts for conducting air from said drum into the intake of said blower, a chute leading from said casing for the discharge therethrough of the material screened out of said air stream, a stripper roll mounted at the inner end of said chute and in cooperative relationship to said drum, said stripper roll having 35 yielding blades arranged to wipe against the peripheral surface of said drum to remove therefrom the accumulation of fiber on said surface and to direct the material so removed through said chute, an intake funnel for conducting the incoming fiber laden air stream into said screening 40 chamber, said casing and said funnel having removable parts constructed for the connection of said funnel to said casing in different operative relationships to said screening chamber, said 45 casing supporting said blower, drum and roll in closely adjacent relationship and cooperating therewith to form a compact, portable condenser unit.

9. A condenser unit for screening fibers out of an air stream, comprising an open-ended rotary screening drum, a blower, a casing having chambers 50 in which said drum and blower are mounted, respectively, with their axes parallel to each other, said casing having ducts for conducting air from said drum into the intake of said blower, means for stripping from said drum the fibrous material strained out of the air stream by the screening surface of the drum, a driving shaft 55 for said blower, and means supporting the rotor casing of the blower for adjustment in its chamber and about said shaft to discharge its air in different directions while maintaining its operative relationship to said drum undisturbed.

10. A condenser unit for screening fibers out

of an air stream, comprising an open-ended rotary screening drum, a blower, a casing having chambers in which said drum and blower are mounted, respectively, with their axes parallel to each other, said casing comprising two sections 5 containing said respective chambers, each of said sections having ducts at opposite sides thereof, the ducts of one section being connected with those of the other to conduct air from the ends of said drum into the intake ends of said blower, means for removing from said drum the fibrous material strained out of the air stream by the screening surface of the drum, and means for securing said sections together in different relationships with said ducts operatively connected with each other.

11. A condenser unit for screening fibers out of an air stream, comprising an open-ended rotary screening drum, a blower, a casing having chambers 10 in which said drum and blower are mounted, respectively, with their axes parallel to each other, said casing having ducts for conducting air from said drum into the intake of said blower, means for stripping from said drum the fibrous material strained out of the air stream by the screening surface of the drum and discharging such material from said casing, said casing comprising two sections containing said respective chambers, means for securing said sections together in different relationships while preserving the cooperative relation of said blower, 15 drum and ducts to each other, the blower section of said casing including end plates, and means supporting the rotor casing of said blower between said plates for adjustment around the blower shaft into different operative positions.

12. A condenser unit for screening fibers out of an air stream, comprising an open-ended rotary screening drum, a blower, a casing having chambers 20 in which said drum and blower are mounted, respectively, with their axes parallel to each other, said casing having ducts for conducting air from said drum into the intake of said blower, the blower section of said casing including end plates to which the walls of said ducts are secured and the blower including a fan and a shaft therefor, bearings for said shaft supported in the outer walls of said ducts, the rotor casing for said blower being secured to said end plates for adjustment around said shaft and into different positions, in all of which its operative relationship to said ducts and said drum is maintained, said blower casing section being adapted to be secured to the section of the casing in which said drum is mounted in either of two operative relationships to the latter, and means for securing said casing sections together.

13. A condenser unit for screening fibers out of an air stream, comprising an open-ended rotary screening drum, a blower, a casing having chambers 25 in which said drum and blower are mounted, respectively, with their axes parallel to each other, said casing having ducts for conducting air from said drum into the intake of said blower, said casing comprising two sections containing said respective chambers, said sections being adapted to be connected together in different operative relationships, each of said sections being composed chiefly of metal plates provided with flanged edges, and means for securing the flanges 30 of the plates of the two sections together in said relationships.

WILLIAM SHAW.
ELIOT B. MACLEAN.
